UNITED STATES PATENT OFFICE

159,598

COMPOSITE CABINET

Catherine Chadwick, Chicago, Ill.

Application September 20, 1947, Serial No. 141,525

Term of patent 14 years

(Cl. D33—19)

To all whom it may concern:

Be it known that I, Catherine Chadwick, a citizen of the United States, residing at Chicago, in the county of Cook and State of Illinois, have invented a new, original, and ornamental Design for a Composite Cabinet, of which the following is a specification, reference being had to the accompanying drawing, forming a part thereof.

Fig. 1 is a perspective view of the composite cabinet embodying my new design.

Fig. 2 is a top plan view.

I claim:

The ornamental design for a composite cabinet, substantially as shown.

CATHERINE CHADWICK.
